UNITED STATES PATENT OFFICE.

LAWRENCE E. JOHNSON, OF MELROSE, MASSACHUSETTS, ASSIGNOR TO VICTOR SHOE MACHINERY CO. OF 1919, OF LYNN, MASSACHUSETTS, A CORPORATION OF MASSACHUSETTS.

ROUGH ROUNDER AND CHANNELING MACHINE.

Application filed September 22, 1922. Serial No. 589,902.

To all whom it may concern:

Be it known that I, LAWRENCE E. JOHNSON, a citizen of the United States of America and a resident of Melrose, in the county of Middlesex and State of Massachusetts, have invented certain new and useful Improvements in Rough Rounders and Channeling Machines, of which the following is a specification.

10 This invention relates to rough rounders and channeling machines to be used in the manufacture of boots and shoes and is an improvement on the machine shown and described in U. S. Patent No. 1,149,369, issued 15 to me August 10, 1915.

The main object of the present invention is to provide mechanism whereby the knife supporting block may be held in firm contact with the work during certain operations of the machine, and in light contact during other operations.

The invention consists in cam actuated mechanism which will automatically vary the tension of the spring for forcing the 25 knife block against the work so that during each cycle of the driving shaft of the machine, a firm hold of the knife block on the work is attained for a certain period, and a light contact between these elements is 30 assured during the remainder of the cycle.

The invention further consists in certain novel features of construction and arrangement of parts which will be understood readily by reference to the description of the 35 drawings and to the claims to be hereinafter given.

For the purpose of illustrating the invention, one preferred form thereof is shown in the drawings, this form having been found 40 to give satisfactory and reliable results, although it is to be understood that the various instrumentalities of which the invention consists can be variously arranged and organized, and that the invention is not limited to the precise arrangement and organization of the instrumentalities as herein shown and described; except as required by the scope of the appended claims.

Of the drawings:

50 Figure 1 represents a front elevation of a

machine embodying the principles of the present invention.

Figure 2 represents a side elevation of the same.

Figure 3 represents a plan of said machine. 55

Figure 4 represents a detail in elevation of a portion of the machine to be herein-after referred to.

Figure 5 represents a rear elevation of 60 the work support.

Figure 6 represents a horizontal section of same on line 6, 6 on Fig. 5, and

Figure 7 represents a rear elevation of a feeding member adapted to be substituted 65 for the channeling knife when the machine is being used for cutting a channel in a sole already shaped, said view being drawn to an enlarged scale.

Similar characters indicate like parts 70 throughout the several figures of the drawings.

In the drawings, 10 is the base of a frame 11, having bearings 12, in which is revolubly mounted a shaft 13 adapted to be driven by 75 a pulley 14 loosely mounted thereon.

The shaft 13 has secured thereto the cam disk 15 and the eccentric 16 and 17. This shaft 13 has also secured thereto a fly wheel 18. 80

The pulley 14 is provided with a hub 19, having a flange 20 thereon, with which contacts the pins 21 secured in the forked end of a lever 22 mounted upon a fulcrum pin 23, said lever 22 having an arm 24 extending therefrom, the outer end of which is connected by means of a rod 25 to a suitable treadle mechanism, which may be of any well known construction and consequently is not shown in the drawings. 85

When the treadle mechanism is operated to depress the arm 24, the lever 22 will cause the pulley 14 to be moved into a frictional engagement with the fly wheel 18, in this manner effecting the rotation of the shaft 13. 95 As soon as the pressure is released from the treadle mechanism, the pulley 14 will move outwardly on the shaft 13 and disengage itself from the fly wheel 18.

The fulcrum pin 23 is mounted on the 100

outer end of a bracket 26 secured to a column 27, to the upper end of which the base 10 is secured.

The frame 11 has extending therefrom a pin 28 on which is mounted the lever 29, the lower end of which is provided with a roll 30, bearing against the cam 15. This lever 30 is provided with a downward extension 31 between which and the pin 32 on the base 10 is a spring 33 which retains the roll 30 in contact with the periphery of the cam 15 at all times.

The upper end of the lever 29 is provided with a bearing 34 in which is mounted a shank 35, the upper end of which is forked as shown at 36 in Figure 1 of the drawings. Between the forked end 36 and the upper end of the bearing 34 is a spring 37, which forces the forked end 36 upwardly. Pivoted to the lever 29 at 38 is a lever 39 having formed therein a slot 40, into which extends a pin 41 secured to and extending outwardly from the shank 35. By means of this lever 39, the shank 35 and the forked upper end 36 thereof may be moved downwardly in the bearing 34 against the tension of the spring 37. This movement is performed when it is desired to insert new work to be operated upon, and as soon as the new work is properly positioned, the pressure upon the lever 39 is released and the spring 37 moves the work upwardly against the member 42.

This member 42 is slidably mounted upon the plate 43, secured to or formed integral with the upper end of the frame 11, said plate 43 extending into a groove in the under face of the member 42 and forming a guide therefor. This slideable member is provided on one side with a slot 44, in which is positioned a lever 45 pivoted to the frame 11 by means of a fixed pivot 46, and having at its upper end an operating handle 47.

The walls of the slot 44 are curved and bear against the edges of the lever 45 so that when the operator actuates the handle 47, the member 42 may be adjusted lengthwise of the plate 43, and secured in an adjusted position by means of the clamping bolt 50 extending through a slot 51 in the slideable member 42.

The front end of the slideable member 42 has an opening 52 extending therethrough, in which is positioned the operating end of the presser foot or work-feeding member 54.

The rear end of the presser foot 54 extends through a transverse slot in the upper end of a rod 55 and is clamped in position therein by means of a nut 56. By releasing this nut 56 from contact with the work-feeding member 54, the said presser foot 54 may be moved endwise in the slot and again clamped to the member 55 in its adjusted position relatively thereto.

The rod 55 extends through a bearing in 65 a member 57 adapted to oscillate about a fulcrum pin 58 secured to the frame 11, and projecting through a downwardly extending flange 57² on said member 57.

The lower end of the rod 55 is secured 70 in a housing 59 having a cylindrical opening therethrough, fitted to the eccentric 17.

When the shaft 13 is rotated, the rotation of the eccentric 17 will cause the rod 55 to be raised and lowered, and also tilted about the axis of the fulcrum pin 58. As a consequence of this movement, the operating end of the work-feeding member, or presser foot, 54, will be brought into contact with the work and impinge thereon, 80 and then move the work a slight distance before said operating end of said presser foot 54 is again raised from contact with said work to return to its normal position.

The front end of the plate 43 has secured 85 thereto a welt gage 60 by means of a screw 61. Beneath the gage 60 is the chisel 62.

The chisel 62 is secured by means of a screw 63, or some other device, to a vertical rod 64 mounted in a bearing 65 in the frame 90 11, and having its lower end clamped to a split member 66 by means of the screw 67.

This member 66 extends through a bearing 68 in a member 69, the lower end of which is provided with a cylindrical opening 95 therethrough to receive the eccentric 16.

As the shaft 13 rotates, the revolution of the eccentric 16 will cause the chisel supporting member 64 to be reciprocated in its bearing 65. When in the extreme of its upper movement, the edge of the chisel 62 is embedded slightly in the lower face of the welt gage 60, which is made of bronze or some similar soft material so as not to injure the cutting edge of said chisel. 105

The front end of the welt gage 60 extends beyond the sides of the plate 43 and is rounded off as indicated at 70 to permit the shoe to be moved horizontally at various angles while in contact therewith. 110

While the channel is being cut the cutting edge of the chisel 62 is embedded in the welt gage 60 and prevents the work from being moved during the cutting operation of the channeling tool. 115

The forked end 36 has mounted therein a block 71 supported upon the alined pins 72, thus providing a means whereby said block 71 may be tilted to accommodate itself to various inclinations of the work during the 120 channeling operation. The tilting of the block 71 is limited in one direction by the block coming into contact with the upper face of the forked portion 36, while the movement in the opposite direction is 125 limited by means of a downwardly extending pin 73 coming into contact with the rear face of said forked portion 36.

The rear end of the block 71 has a vertical groove formed therein, in which is mounted the body portion of the channeling knife 74, the operating end of which extends towards the front of the block with its edge substantially parallel to the upper face of said block.

One edge of the body portion of the channeling knife 74 is bevelled and coacts with a bevelled part of an adjustable pin 75, extending from the rear of the block 71 beyond the front face thereof, and having a clamping nut 76 threaded to the projecting end thereof. By turning the nut 76 the channeling knife 74 may be clamped in any desired position. By loosening the nut, the channeling knife may be adjusted to give varying degrees of cut during the formation of the channel.

The upper end of the block 71 is cut away below the operating end of the channeling knife 74 so that when it is desired to use the machine for rough rounding without forming a channel, the channeling knife 74 may be moved down below the upper face of the block so that no cutting operation will be performed. This cut away portion beneath the operating part of the channeling knife also provides a means for taking care of the chips formed during the cutting of the channel.

The shank 36 has a longitudinal slot 77 cut in its lower end, through which extends the lever 39. This construction provides a means for preventing the rotation of the shank 36 within its bearing 34.

In the frame 11 is mounted a shaft 78 having an operating handle 79 secured to one end thereof. The opposite end of this shaft 78 has a projecting lug 80 radiating therefrom. This lug 80 extends into an annular groove 81 in the rear end of the pin 28, on which the lever 29 is mounted.

By actuating the handle 79 this pin 28 and all of the parts supported thereon may be moved lengthwise of the axis of said pin 28 into any desired position. This construction provides a means whereby the position of the operating end of the channeling knife may be adjusted longitudinally relatively to the welt gage 60 and the chisel 62.

The eccentrics 16 and 17 are so timed that in the operation of the machine the presser foot 54 and chisel 62 are both at their highest point at the same time, and the cam 15 is so constructed as to permit the cutting operation of the knife 74 to take place at the same time that the chisel 62 and the presser foot 54 are in their highest positions. As a consequence of this condition, the chisel 62 will be in the work when the knife 74 is cutting the work to form a channel therein. Therefore, the chisel 62 will hold the

work from lateral movement during the channel cutting operation.

The various elements are shown in this position in the drawings with the cutting knife 74 about midway of its stroke.

As thus far described, the machine is substantially the same as that shown in another application, Ser. No. 527,344, filed January 6, 1922, by Otto T. Peterson, Leonard A. Popp, and myself, and on which the invention shown and described in the present application is an improvement.

In operating the machine shown and described in the earlier application above referred to, difficulty was found in feeding the work and also in holding the work against the edge gage, this difficulty being due to a heavy spring 37 used.

It was found desirable under certain conditions to provide some mechanism which would have the same effect as a heavy spring while the channel knife is cutting the channel and the chisel is withdrawn from the work, and which would have the effect of a much lighter spring under all other conditions.

To obtain this object, the following mechanism has been added to the original machine, and this mechanism is the subject matter of the invention sought to be covered by the present application.

The cam 15 has secured to its rear face a cam 105, or the two cams 15, 105 may be formed integral if desired. The cam 105 coacts with a roller 106 rotatable upon a stud 107 secured in the free end of a lever 108, the opposite end of which is pivotally secured to the lever 29.

The free end of the lever 108 has an upwardly extending ear 109 provided with a pivot pin 110 extending through the lower end of the bar 111 to the upper end of which is secured a horizontal plate 112 having an opening therein, through which extends the shank 35 of the forked member 36.

The spring 37 rests upon this plate 112, and not upon the upper end of the bearing 34 as in the other application, Ser. No. 527,344.

A much lighter spring 37 may be used with this construction than could be used with the construction shown and described in the earlier application.

The shaft 13 rotates in the direction of the arrow *a* on Figure 1 of the drawings, and as the eccentrics 16 and 17 rotate therewith, the presser foot 54 and chisel 62 will immediately commence to move downwardly as these eccentrics 16 and 17 rotate from the positions indicated in the drawings, while the knife 74 will first complete the other half of its cutting stroke and then remain stationary until the point 83 of the cam 15 reaches the roller 30, and at this time the

knife 74 will be moved to the left of Fig. 1, preparatory to a new cutting stroke which commences when the point 84 on the cam 15 reaches the roller 30.

6 The eccentric 16 has a greater throw than the eccentric 17, owing to the thickness of the work, and as a consequence the presser foot 54 will come into contact with the work preparatory to feeding just before the chisel 62 has left the work, and this work will then be fed a predetermined distance before the chisel 62 on its return stroke again enters the work.

10 15 The presser foot 54, having completed this feeding operation, will again be lifted from the work. The chisel 62 will be forced through a new part of the work and the channeling knife 74 will cut a new part of the channel in the sole.

20 25 It will be seen that by the construction herein shown and described, the stroke of the knife 74 is divided on opposite sides of a center line perpendicular to the face of the sole being cut, thereby producing a clean-cut channel. This obviously is a great advantage.

On the return stroke of the cutting knife 74, the presser foot 54 is in contact with the work which is gripped between said presser 30 foot 54 and the knife 74 and in this manner the work is positively fed a predetermined distance preparatory to another cutting stroke of said knife 74.

35 By constructing the machine as herein shown and described, it is possible to cut the channel in the work even when the chisel 62 is not in the work, as for instance, when the channel is to be cut close to the edge of the sole and consequently the edge 40 of said sole will not extend outwardly a sufficient distance to be acted upon by said chisel.

45 As shown in the drawings, when the channeling knife is cutting the channel the roller 106 is on the high point of the cam 105, thereby causing the plate 112 to be in raised position and increasing the tension of the spring 37.

50 This increased tension of the spring 37 continues during the cutting of the channel and the withdrawal of the chisel from the work.

55 By the time these operations are completed, the high point of the cam 105 has passed from beneath the roller 106, permitting the plate 112 to move downwardly onto the upper face of the bearing 34.

60 The tension of the spring will be greatly reduced when permitted to expand by the downward movement of the plate 112, but the tension will still be sufficient to force upwardly the forked member 36, against the work to be operated upon.

65 Owing to the reduction in the tension of

the spring 37, the operator is enabled to feed the work more freely and also to hold the work more easily against the edge gage.

70 By the use of a lighter spring 37, the wear upon the movable parts is reduced to a minimum.

75 It will be noted that by means of the new mechanism herein described, the block 71 is held firmly against the work when a firm hold is desired, and at all other times when such firm hold is unnecessary, a light contact is retained between said block and work.

80 This makes a very simple construction of machine for rough rounding soles and cutting the channels therein, which may be used for rough rounding alone or for rough rounding and channelling. The machine is also adapted to rough round soles of new shoes during the process of construction, or old shoes during the process of repairing.

85 When completed shoes are being operated upon, the end of the member 42 may be used as a gage while bearing against the upper. When the machine is being used as a rough rounder without cutting a channel in the sole, the knife 74 is preferably removed and the feeding member 74^x inserted in its place. The upper face of the member 74^x is preferably provided with a plurality of serrations 85 as indicated in Fig. 7. With this member 74^x in use, the presser foot 54 will force the work into contact with the serrations 85 and feed the work a predetermined distance on the return stroke of the work support 36 preparatory to another cutting 100 operation of the chisel 62.

105 The fulcrum pin 28 is provided with a flange 86 which is adapted to contact with the end of the bearing 87 for the pin 28 in the frame 11, thereby limiting the movement of said pin 28 in one direction, while movement thereof in the opposite direction is limited by the projecting lug 80 coming into contact with the opposite face of said bearing 87.

110 When the fulcrum pin 28 has been adjusted to any desired position, it may be secured in such position by means of the clamp nut 88.

115 It will be noted that the cam 15 is so constructed as to provide a quick cutting stroke to the knife 74 and a very slow return to normal position.

120 It is believed that the operation and many advantages of the invention will be readily understood without further description.

125 Having thus described my invention, I claim:

1. In a machine of the class described, the combination of a welt gage; a work support; a channeling knife mounted therein; a non-revoluble shank to said work support; a cam-actuated rocker member having a

bearing at one end to receive said shank; a spring for forcing said work support toward said welt gage; and means for increasing the tension of said spring when the channeling knife is operating.

2. In a machine of the class described, the combination of a welt gage; a work support; a channeling knife mounted therein; a non-revolvle shank to said work support; a cam-actuated rocker member having a bearing at one end to receive said shank; a spring for forcing said work support toward said welt gage; and means for automatically increasing the tension of said spring when the channeling knife is operating.

3. In a machine of the class described, the combination of a welt gage; a work support; a channeling knife mounted therein; a non-revolvle shank to said work support; a cam-actuated rocker member having a bearing at one end to receive said shank; a spring for forcing said work support toward said welt gage; a plate surrounding said shank beneath said spring; and cam-actuated mechanism for moving said plate and compressing said spring when the channeling knife is operating.

4. In a machine of the class described, the combination of a welt gage; a work support; a channeling knife mounted therein; a non-revolvle shank to said work support; a cam-actuated rocker member having a bearing at one end to receive said shank; a spring for forcing said work support toward said welt gage; a plate surrounding said shank beneath said spring; a bar depending therefrom; and cam mechanism for raising said bar and plate.

5. In a machine of the class described, the combination of a welt gage; a work support; a channeling knife mounted therein; a non-revolvle shank to said work support; a cam-actuated rocker member having a bearing at one end to receive said

shank; a spring for forcing said work support toward said welt gage; a plate surrounding said shank beneath said spring; a bar depending therefrom; a pivoted lever the free end of which is pivotally connected to the lower end of said bar; and a cam for moving said lever about its pivot.

6. In a device of the class described, the combination of a welt gage; a work support having a non-revolvle shank; a channeling knife in said work support; a rocker member having a bearing at one end for said shank; a spring surrounding said shank between said bearing and work support; a plate beneath said spring; a bar depending from said plate; a lever pivoted to said rocker member with its free end pivotally connected to the lower end of said bar; a revoluble shaft; and cams thereon for actuating said rocker member and moving said lever about its pivot.

7. In a device of the class described, the combination of a welt gage; a work support having a non-revolvle shank; a channeling knife in said work support; a rocker member having a bearing at one end for said shank; a spring surrounding said shank between said bearing and work support; a plate beneath said spring; a bar depending from said plate; a lever pivoted to said rocker member with its free end pivotally connected to the lower end of said bar; a roller on the lower end of said rocker member; a roller on the free end of said lever; a revoluble shaft; and a separate cam secured to said shaft to coat with each of said rollers.

Signed by me at 746 Old South Bldg., Boston, Mass., this 18th day of September, 1922.

LAWRENCE E. JOHNSON.
